DESIGN FOR A DESK SUPPORT

William J. Bargen, Waukegan, Ill.

Application March 13, 1940, Serial No. 90,903

Term of patent 14 years

To all whom it may concern:

Be it known that I, William J. Bargen, a citizen of the United States, residing at Waukegan, in the county of Lake and State of Illinois, have invented a new, original, and ornamental Design for a Desk Support, of which the following is a specification, reference being had to the accompanying drawing, forming a part thereof.

In the drawing:

I claim:

The ornamental design for a desk support, as shown.

WILLIAM J. BARGEN.
